[57] **ABSTRACT**

An electrode sealing packing of an electric arc furnace is characterized in that it comprises at least two rows of movable packing segments radially pressed against the electrode by a tightening device and disposed one above another on a water-cooled box mounted on a furnace roof in the zone of an electrode opening; said tightening device is made in the form of a weight ring with tightening rods whose one end is articulated with the weight ring and the other with the packing segments ensuring the clamping of the segments to the electrode on account of the weight of the ring with the lateral edges of a packing segment of the lower row being parallel to the axis of motion of the segment and the spacings between the packing segments of the lower row accommodating plates similar in shape to that of the spacings, the plates being rigidly connected with each other forming a ring loosely resting on the water-cooled box.

FIG. 2

FIG. 1

PACKING OF ELECTRODES IN AN ELECTRIC ARC FURNACE

The present invention relates to steel-melting electric arc furnaces, where the problem of efficient packing of a gap between an electrode and a furnace roof is most acute due to specific features peculiar to the technology of production of electric steel and constructional characteristics of metallurgical units in question; and more particularly the present invention is directed to packing of electrodes in electric arc furnaces.

Known at present are various kinds of electrode packings of diversified design, which may be subdivided into three groups.

The first one includes devices in which packing is provided by some mechanical means.

The second group comprises devices in which packing is effected by blowing gas /air or nitrogen/ into a gap between the electrode and the roof.

The third group comprises composite devices which represent a combination of the first two groups.

Known in prior art is an electrode packing of the mechanical type, made in the form of a ring of either ceramic or metallic segments encompassing the electrode above a watercooled box, with each segment articulated with a weight suspended in such a manner that a "moment" of said weight produced ensures a constant force pressing the segments against the electrode.

However the above electrode packing is too cumbersome and does not provide dependable and trouble-free operation.

Also known is an electrode packing in the form of a collar made up of several segments articulated with each other by means of pins. The extreme segments in this arrangement are fitted with arms from which a load chain is suspended with the weight component of the chain producing a force pressing the segments against the electrode.

The aforesaid arrangement however does not ensure an efficient packing of electrodes of variable cross-section.

Known also is an electrode packing which consists of a set of plates assembled in packs to rock about a pivot.

The plate packs disposed along the electrode perimeter are fastened on a water-cooled box.

The pivot holes in the plates are displaced toward the electrode relative to the plate center of gravity, producing a moment of the plate weight which assures a constant force pressing the plates against the electrode.

In operation the spacings between adjoining plates are liable to collect dust and are exposed to schorching, by which virtue the plates loose their mobility and the device becomes non-serviceable.

Known in the prior art is an electrode packing made up of individual cooled sections disposed in two rows around the electrode.

The exterior of the sections in the inner row facing the electrode conform to the electrode shape.

The sections are loosely suspended from arms held by rollers at a certain angle to the horizontal so that their weight component creates a force holding them tight to the electrode. The rollers are secured to the supports of a ring-shaped sheet mounted on a roof lining. Joints between individual sections are overlapped

by a row of external sections articulated with the latter by means of arms.

Spacings between the section collar and the ring-shaped sheet are overlapped by two rows of sheet sectors with the lower one being coupled with mobile sections and the upper - with the stationary ring-shaped sheet.

The above packing devices have too sophisticated a construction and inadequate efficiency.

Apart from the varieties of electrode packings stated above in which the problem of providing a packing in a gap between an electrode and a roof is solved by mechanical means, known also is an electrode packing, in which the packing action is provided by a gas /air or nitrogen/ into the gap between the electrode and the furnace roof.

However such electrode packings are not dependable enough in service and do not provide an efficient sealing of the electrodes. Also inherent in mechanical packings is either low efficiency or an intricate construction and inadequate reliability in operation.

Dynamic gas packings tend to cause an intense oxidation of the electrodes and either hamper the production of a reducing atmosphere in the furnace / in case air is blown/ or are extremely expensive /where nitrogen is employed for blowing in/. Composite packings suffer from the drawbacks peculiar to both types.

Owing to the foregoing disadvantages none of the conventional electrode packings has received wide application particularly due to shortcomings inherent in each type.

It is an object of the present invention to eliminate the above said drawbacks.

The present invention is in essence aimed at developing a packing for electrodes of an electric arc furnace which would be reliable in operation ensuring an efficient sealing of a gap between each electrode and the furnace roof at the same time featuring adequate overall dimensions, ease of maintenance and lack of sensitivity to thermal loads.

According to this invention, the specified object is achieved by the fact that in an electrode packing developed for an electric arc furnace a tightening device is made in the form of a weight ring with tightening rods articulated with one end with a weight ring while their other end is hinged to mobile segments, by virtue of which the segments are clamped to the electrode due to the ring weight, with the lateral edges of each segment in a lower row being parallel to an axis of motion of the segment and with spacings between the adjoining segments accommodating plates similar in shape to that of the spacings.

It is expedient to connect the plates rigidly with each other to form a ring resting freely on a water-cooled box and to hold the plates in place with the aid of the segments in setting up and removing them from the cooled box.

In compliance with the present invention, the proposed electrode packing provides for an efficient sealing of the gaps between the electrode and the roof, reducing heat losses to a permissible value and improving atmospheric conditions in a shop.

It is noteworthy that simple construction and small overall dimensions of the proposed device result in high

reliability and convenience in maintenance along with thermal stability.

The electrode packing is best suited for electric arc steel-melting furnaces, and especially for such furnaces as are equipped with units for the removal of furnace gases directly from the furnace working chamber.

In addition it is also applicable in electrothermal apparatus with mobile electrodes passing through the roof, where tightening of the gap between the electrode and the furnace roof to an ideal level is not required.

Given below is a description of a design of the proposed device and its operation to be considered with due reference to the appended drawings, wherein:

FIG. 1 is a cross-sectional view of electrode packing, conforming to the invention.

FIG. 2 shows a top view of FIG. 1 with a weight ring and an upper row of segments shown fragmentary.

With reference to the figures an electrode packing consists of a water-cooled box 1 mounted on a furnace roof in the zone of an electrode opening, mobile segments 2 and 3 arranged in two rows—an upper and a lower one accordingly, clamped by a tightening device comprising tightening rods 4 linked mechanically with each other and a weight ring 5. Packing segments 2 and 3 of the upper and lower rows respectively are articulated by means of tightening rods 4 with weight ring 5. This is effected with the aid of pins 6 passing through ears 7 of the weight ring and ears 8 of packing segments 2 and 3. Ears 8 act as the guides for the packing segments 2 and 3.

Lateral edges of packing segments 3 of the lower row are parallel to the axes of motion of segments 3, directed toward the center point of electrode 9. The spacings between the packing segments 3 of the lower row accommodate plates 10 similar in shape to that of the spacings and equal in thickness to that of packing segments 3. Plates 10 are rigidly coupled with each other by means of ring 11. An inner diameter of ring 11 is slightly smaller than the outer diameter of the lower row of packing segments 3 to enable ring 11 to be raised with plates 10 by packing segments during erection and removal.

The electrode packing functions as follows. Ring-shaped water-cooled box 1 protects a region of the lining of furnace roof 12 adjoining electrode 9 and mechanical elements incorporated in the packing construction from excessive heat. For better sealing of the proposed device water-cooled box 1 is mounted on refractory layer 13 applied to the lining of roof 12 in the zone of electrode opening 14. With the proposed arrangement packing segments 2 and 3 made of heat-resistant low-magnetic material (for example, of a heat-proof alloy of an austenitic class or of a non-metallic refractory material of the type of a graphite-containing ceramics) acts as the main packing element. For better overlapping of the gap between electrode 9 and water-cooled box 1 mobile packing segments 2 and 3 are arranged in two rows overlapping so that the gaps between packing segments 3 in the lower row overlap

gaps of segments 2 in the upper row. Owing to a sloped arrangement of tightening rods 4 a force produced by the weight of ring 5 presses packing segments 2 and 3 radially against electrode 9 ensuring thereby a minimum value of straight vertical gaps in the packing. Both the gaps between the adjoining packing segments 2 and 3 and the angle of inclination of rods 4 are so chosen as to ensure the clamping of packing segments 2 and 3 to electrode 9 with a cone-shaped working end therefor. When a new electrode 9 with a cylindrical end is inserted into the packing, segments 2 and 3 are moved apart by ears 8 provided on packing segments 2 and 3 and acting at one and the same time as the lugs for fastening rods 4. The spacing between packing segments 3 of the lower row needed to ensure their radial movement in a horizontal plane are overlapped by plates 10. The lateral edges of packing segments 3 being parallel to their axes of respective displacement plates 10 do not interfere with the movement of packing segments 2 and 3 under the action of weight ring 5 with a minimum value of the straight gaps between plates and segments 2 and 3. Being rigidly coupled with each other by means of ring 11 plates 10 are freely resting on water-cooled box 1, through which the entire packing system is self-aligning with electrode 9.

In setting up and removing weight ring 5 with packing segments 2 and 3 on cooled box 1, ring 11 together with plates 10 is held in place by the lower row 30 of packing segments 3, being set up or taken off together with the latter.

WHAT IS CLAIMED IS:

1. An electrode packing arrangement to seal an electrode where it enters an electric arc furnace, comprising: a water-cooled box, mounted on a furnace roof in the zone of an opening in the furnace through which opening the electrode is introduced; at least two rows of packing segments, arranged one above the other on said water-cooled box to constitute lower and upper rows; a tightening device clamping said packing segments and radially biasing the segments into sealing engagement with the electrode, said tightening device made in the form of a weight-ring with tightening rods one end of each of the rods being articulated with the weight-ring and the other end of each of said rods being articulated with the packing segments ensuring the pressing of the segments against the electrode on account of the weight of the weight-ring, with lateral edges of one segment of the lower row being parallel to the axis of motion of said one segment; plates disposed in spacings between adjacent packing segments of the lower row and similar in shape to that of the spacings.

2. An electrode packing for an electric arc furnace, as in Claim 1, in which said plates are rigidly coupled with each other forming a ring loosely resting on the water-cooled box and held in place by the packing segments in their setting up and removal from the water-cooled box.
